UNITED STATES PATENT OFFICE.

GEORGE W. GANOE, OF PHILIPSBURG, PENNSYLVANIA, ASSIGNOR, BY DIRECT AND MESNE ASSIGNMENTS, OF TWO-THIRDS TO WILLIAM C. PRICKETT AND JOHN S. FURST, OF WILLIAMSPORT, PENNSYLVANIA.

TELEPHONE ATTACHMENT.

SPECIFICATION forming part of Letters Patent No. 664,941, dated January 1, 1901.
Application filed July 2, 1900. Serial No. 22,340. (No model.)

To all whom it may concern:

Be it known that I, GEORGE WESLEY GANOE, a citizen of the United States, residing at Philipsburg, in the county of Centre and State of Pennsylvania, have invented a new and useful Telephone Attachment, of which the following is a specification.

This invention relates to telephone attachments, and pertains more particularly to means for supporting a receiver or earpiece in convenient relation to a transmitter.

The object of the invention is to provide simple and effective means for normally supporting a telephone-receiver in operative position in front of a transmitter in a movable manner, whereby the approach of the user of the instrument in operative proximity to the latter will necessitate a lateral swing of the attachment holding the receiver and thereby automatically actuate a switch to close the circuit and throw in the receiver and transmitter and maintain the latter in such condition until use of the entire instrument is completed, when the attachment and receiver will be automatically returned to normal position and the switch reversely operated to open the circuit.

The invention primarily consists in the utilization of an outwardly-projecting arm pivotally or movably attached to a support at its inner end and connected to a switch for controlling the telephone-circuit, automatic means for returning the arm to its normal position, and means for holding a receiver or earpiece in the outer end of said arm in such position that when used it will occupy a convenient position relatively to the ear of the operator, the transmitter being inaccessible until the arm and receiver are moved from normal place in front of the same, but without requiring the receiver to be held in the hand, as in ordinary methods.

The invention further consists in the construction and arrangement of the several parts, which will be more fully hereinafter described and claimed.

In the drawings, Figure 1 is a perspective view of a complete telephone instrument embodying the features of the invention. Fig. 2 is a detail perspective view of the attach-

ment, showing a portion separated therefrom. Fig. 3 is a detail-sectional elevation of another portion of the attachment. Fig. 4 is a detail perspective view of the cap-block for the device shown by Fig. 3. Fig. 5 is a detail perspective view of a modified construction for returning the arm to its normal position.

Similar numerals of reference are employed to indicate corresponding parts in the several views.

The numeral 1 designates a subscriber's telephone complement and includes a back-board or support 2 and a transmitter 3, provided with a switch member 4, which in the present instance is shown in the form of the usual spring-actuated fork 5, extending from one side of the transmitter-box. The successful operation of the improved attachment is not dependent on the use of an exact form of switch member, as it can be applied to telephone outfits having various forms of said member applicable for the purpose of the present construction.

The improved attachment comprises an arm 6, which is shown as formed with an intermediate frictional joint 7 to permit the outer extremity to be raised or lowered to accommodate the heights of different users or operators. The rear end of the arm is pivotally held between ears 8, extending outwardly from the vertical or depending member of an angle-bracket 9, the upper horizontal shorter member of the latter being formed with a slot 10 for adjustable arrangement in rear of the upper edge of one side of the support or back-board 2, the fastening device 11 for securing the one upper corner portion of the said support or backboard being also passed through the slot 10 and forming the sole means in addition to the support or backboard pressure on the horizontal member of the bracket for holding the latter in desired position. At any time desired and to accommodate different applications the bracket may be adjusted to move the vertically-depending member 95 thereof outwardly from or inwardly toward the adjacent side edge of the support or back-board. Below the ears 8 is a keeper 12, which is rigidly attached to the vertically-depending member of the bracket and has its outer 100

extremity inturned, as at 13, and formed with a reduced inwardly-directed terminal 14 to provide a seat 15, over which is fitted one terminal of a coiled spring 16, having its opposite terminal also applied over a projection or pin 17 on the adjacent edge of the arm, near the pivotal point of the latter. The said spring 16 throws the arm inwardly toward the transmitter-box a certain prearranged distance, and the outward movement of the said arm is exerted against the resistance of the said spring. The outer end of the arm is provided with an upstanding angular support 18, having a reduced screw-threaded terminal 19 to receive a nut 20 and ears 21 of a cylindrical clamp against which the said nut has bearing. The clamp 22 is fitted over the body of a receiver 23, and the latter is held by the said clamp in a plane at right angles to the arm in advance of the front of the transmitter, so that before access can be had to the receiver by a user or operator it will be necessary to push the receiver and arm outwardly in a lateral direction.

In the fork 5 of the switch member 4 a weight 24 is held, and to sustain the said weight in connection with the fork it is provided with a cap-block or head 25, formed with a circumferential groove 26, engaged by the fork and held in secured position on the upper end of the weight by a bolt 27, extending vertically therethrough and into the body of the said weight. The lower end or extremity of the bolt only is screw-threaded, so that the portion thereof that passes through the head or cap-block is smooth and will thereby be prevented from working loose. The upper end of the bolt is formed with an eye 28, and secured thereto is the lower extremity of a cord or other flexible connection 29, secured in one of a series of openings 30 in the arm above at its opposite end. The weight 24 acts to hold the switch member 4 in lowered position to normally open the telephone-circuit, and as an operator or user approaches the transmitter he places his ear against the orifice of the receiver and pushes the arm, carrying the latter outwardly from the transmitter to obtain a proper position in front of the latter. This movement of the arm draws on the connection 29 by reason of the increase of distance in excess of the normal relation of the weight and arm, and consequently the weight is elevated, and with it the switch member, the upward movement of the latter being facilitated when the overpowering influence of the weight is withdrawn therefrom by the spring in connection therewith. This upward movement of the weight and fork 5 closes the telephone-circuit and both the receiver and transmitter are thrown into the line. The instruments remain in this condition as long as the user or operator has the receiver and arm pressed out by contact with the head; but as soon as the receiver is released the spring 16 exerts its force against the arm and returns it and the receiver to

normal position, as shown by Fig. 1. The tendency of the arm and receiver to return to normal position is also encouraged by the weight, in connection with the fork 5 and attached to said arm, also operating, when free to do so, to pull back to place, it being understood that the weight never becomes disengaged from the fork. By changing the connection 29 from one to another of the openings 30 the pulling tension on the weight may be varied, and the throw of the arm will also be correspondingly changed, and switch members having a greater or less degree of movement can be readily accommodated.

Another mode of causing the arm to return to normal position or holding it in prearranged adjustment is shown by Fig. 5, and in this modification the pivot-bolt 31 is projected above the uppermost ear 8 and surrounded by a coiled spring 32, having one extremity bearing against the one edge of the vertically-depending member of the bracket and the other extremity 33 bent at an angle 90° and bearing against the one edge of the said arm. It will be understood that the extremity 33 bears against the outer edge of the arm, so as to throw the latter inwardly, and in some instances this construction may be preferred.

The improved attachment is easily and quickly applied, strong and durable, and, being composed of a comparatively few parts, is inexpensive in manufacture and use. The preferred construction has been illustrated and descriptively disclosed; but many modifications can be adopted, among which may be mentioned the obvious expedient of dispensing with all springs to return the arm to normal position and arranging the pivot pin 105 or bolt thereof at an angle of inclination in such direction that the arm will always have a tendency to ride inwardly when free to so operate. Also changes in the form, size, proportions, and minor details may be resorted 110 to without departing from the principle of the invention.

I desire it understood that the term "flexible" used in this specification is employed in its general or generic sense and not specifically.

Having thus described the invention, what is claimed as new is—

1. In a telephone attachment, the combination with a transmitter having a support and a switch member coacting therewith to control the circuit, of a bracket having a portion adjustably mounted behind the transmitter-support and held by a part of the fastenings of the latter, an arm pivotally mounted to swing horizontally and located adjacent the transmitter, the free end of the said arm having a transmitter held therein and normally obstructing free access to the transmitter, a weight device in engagement with the switch member and normally holding the latter open, and a freely-flexible connection secured to said weight device and adjustably attached to the arm.

2. In a telephone attachment, the combination with a transmitter having a switch, of an arm pivotally mounted adjacent to the transmitter and having a receiver held in its free end in such position as to obstruct free access to the transmitter, a weight in engagement with the switch and normally holding the latter open, and a flexible device secured to the weight and adjustably attached to the arm whereby a movement of the arm will free the switch of the overpowering force of the weight and permit said switch to close the circuit when the operator gains access to the transmitter.
- 15 3. In a telephone attachment, the combination with a transmitter having a switch co-acting therewith, of an arm movably mounted adjacent to the transmitter and having a receiver held by its free end and obstructing free access to the transmitter, means for maintaining the arm in normal position, a weight having a grooved head engaging the switch, and a flexible connection between the weight and the arm and adjustably attached 25 to the latter.
4. In a telephone attachment, the combination with a transmitter having a switch co-acting therewith, of an arm movably mounted adjacent to the transmitter and having a receiver in its free end, a bracket to which said arm is attached provided with a slotted member engaged by one of the fastenings of the support of the transmitter, means for maintaining the arm in normal position, and means 35 connected to the arm for controlling the switch.
5. In a telephone attachment, the combination with the transmitter and its switch, of a laterally-movable arm located at the side of
- the transmitter in proximity to the switch, 40 and a direct flexible connection between the arm and the switch whereby an outward movement of the arm exerts and causes a perpendicular movement of the switch, substantially as described.
- 45 6. In a telephone attachment, the combination with the transmitter and its switch, of a receiver-supporting arm pivotally secured and located at the side of the transmitter and a direct connection between the arm and switch, arranged to positively actuate the switch upon an outward lateral movement of the arm, substantially as described.
7. In a telephone attachment, the combination with the transmitter, of a switch-arm and 55 means for normally holding the arm down, of a laterally-movable receiver-supporting arm pivotally mounted adjacent to the rear of the transmitter at the side, and a direct connection from the arm to the switch-arm so arranged that the outward movement of the supporting-arm will raise the switch-arm, substantially as described.
8. In a telephone attachment, the combination with the transmitter and its switch, of a 65 receiver-carrying arm pivoted to move laterally and located beyond the horizontal plane of the switch, and a flexible connection between the arm and switch in advance of the pivot of the arm, substantially as described. 70
- In testimony that I claim the foregoing as my own I have hereto affixed my signature in the presence of two witnesses.

GEORGE W. GANOE.
